UNITED STATES PATENT OFFICE.

BENJAMIN ALFRED DOBSON AND WILLIAM ISHERWOOD BROMILEY, OF BOLTON, ENGLAND, ASSIGNORS TO DOBSON & BARLOW, LIMITED, OF SAME PLACE.

COVER FOR CARDING-ENGINES.

SPECIFICATION forming part of Letters Patent No. 588,182, dated August 17, 1897.

Application filed April 26, 1897. Serial No. 633,957. (No model.) Patented in England January 1, 1897, No. 39.

To all whom it may concern:

Be it known that we, BENJAMIN ALFRED DOBSON and WILLIAM ISHERWOOD BROMILEY, subjects of the Queen of Great Britain, residing at Bolton, in the county of Lancaster, England, have invented certain new and useful Improvements in or Relating to Covers for Carding-Engines, (for which we have obtained Letters Patent in Great Britain, No. 39, bearing date January 1, 1897,) and of which the following is a specification.

Our invention relates to the cover employed to inclose the space between the upper surface of the doffer and the main cylinder of a carding-engine. This cover has a hinged door which must be opened for the purpose of grinding and stripping the cylinder, and this may require to be done several times in a day. When by the negligence of the attendant the door is not replaced and the card is put into work again, the stripped waste drops down and conceals the open space. Then when the workman attempts to remove the waste it is caught and carried forward by the wire of the cylinder and in many cases a workman has lost his fingers or even his whole hand.

Our invention consists in preventing the door being left open at any time when the cover is in position unless the grinding-roller or stripping-brush is in its working bearings. We effect this by the mechanism illustrated on the accompanying two sheets of drawings, in which—

Figure 1 is a side elevation, partly in section, of part of the main cylinder and doffer of a carding-engine, showing our improved cover with the door open and the grinding-roller in position. Fig. 2 is a front sectional elevation of part of Fig. 1. Figs. 3, 4, and 5 are three diagrammatic views, Fig. 3 showing the improved cover in the working position with the door closed; Fig. 4, the same with the door open and the grinding-roller in position, and Fig. 5 the cover drawn forward to enable the attendant to get at the space between the cylinder and doffer.

Similar letters refer to similar parts throughout the several views.

The cover *a* is arranged, as usual, to inclose the space between the main cylinder *b* and

doffer *c* of the carding-engine and is movable also, as usual, upon the cheeks or side frames *d* of the doffer by means of the handle *e*, hinged thereto, from the position shown in Figs. 1 and 3 to the position shown in Fig. 5, and vice versa. 55 The cover *d* has the door *f* hinged to it, and according to our invention we apply a device to this door in order to prevent it from being left open except when required for stripping or when the grinding-roller *g* is in position for 60 grinding the card-teeth on the main cylinder, as indicated in Figs. 1, 2, and 4. This device, as illustrated, consists of a lever *h*, the free end of which bears against the outside of the hinged door *f*. The lever *h* is fulcrumed to 65 the engine-bend *i* at *j* and is weighted, say, for example, by the chain and weight *k*, the chain passing over a pulley *l* on the engine-bend *i* and always tending to raise the lever *h* and door *f* into the position indicated in 70 Fig. 3. When, however, the door *f* is opened and the grinding-roller *g* is placed in its usual brackets *m*, secured by bolts *n* to the engine-bend *i*, as indicated in Figs. 1, 2, and 4, a finger *o*, suspended from the axle *p* of the 75 grinding-roller *g*, bears upon the door *f* and holds it open against the weight of the lever *h*, but when the grinding-roller *g* is removed the weighted lever *h* closes the door automatically. Again, when the whole cover *a* is 80 drawn forward by means of the handle *e* into the position indicated in Fig. 5, in order to free the space between the cylinder and doffer, the lever *h* is powerless to close the door *f* when opened on account of the end of the lever 85 coming immediately under the hinge of the door, as clearly shown in the said Fig. 5.

Having now particularly described and ascertained the nature of our said invention and in what manner the same is to be performed, 90 we declare that what we claim, and desire to secure by Letters Patent of the United States, is—

1. In combination, the cylinder, the doffer, a cover between the cylinder and doffer, a door 95 carried by said cover and means for automatically closing said door, substantially as described.

2. In combination with the cylinder and doffer, a movable cover between the cylinder 100

and doffer adapted to be drawn forward from its normal position, a door connected to said cover and means for automatically closing said door when the cover is adjusted to its 5 backward or normal position.

3. In combination with the cylinder and doffer, a cover between the same, a door hinged to the cover and a weighted lever engaging the door to close the same, substantially as described.

4. In combination, the cylinder and doffer, the cover, the door thereon, means for closing the door automatically and the grinding-roller with means for holding the door open when 15 the grinding-roller is in normal position.

5. In combination the cylinder, the doffer, the cover, the door thereon, means for closing the door automatically, the grinding-roller and the finger carried by the axle thereof for

holding the door open, substantially as described.

6. In combination the cylinder, the doffer, the movable cover adapted to be drawn forward from its normal position, a door carried by the cover, and adapted to be moved forward therewith, and means for automatically closing the door when the cover with the door is in its rearward or normal position, the said door when drawn forward by the cover being out of operative engagement with its closing 30 means, substantially as described.

In witness whereof we have hereunto set our hands in presence of two witnesses.

BEN. ALF. DOBSON.

WM. ISHERWOOD BROMILEY.
